APPARATUS FOR ATTACHING SEAL CAPS
ON BOTTLESSven Otto Piehl and Hjalmar Friberg,
Stockholm, SwedenApplication October 17, 1934, Serial No. 748,645
In Sweden October 21, 1933

2 Claims. (Cl. 226—86)

The present invention relates to such apparatus for attaching seal caps on bottles by pressing the skirt of the seal cap into a recess on the outside of the head of the bottle by means of a resilient ring, such apparatus comprising an abutment member for pressing the seal cap axially downwards towards the bottle opening, further a wedge member provided with an inclined guide face in relation to which the resilient ring is to be displaced so as to compress the ring radially, and a pressure member effecting the displacement of the ring in relation to the wedge member.

In previously known apparatus of this kind, the abutment member acting towards the bottle opening and the pressure member acting on the resilient ring have been rigidly interconnected, whereas the wedge member was displaceable in relation to them. The consequence hereof was that after having pressed down the abutment member towards the bottle opening, the bottle head, the abutment member and the pressure member became immovable in relation to each other. When thereupon the wedge member was displaced in relation to said members to compress the ring, the latter obtained therefore a radial motion which was fixed in relation to the abutment and pressure members.

It is, however, a known fact that the size and shape of the bottle neck, for example the position and depth of the bead and the recess are not exact, but subjected to considerable variations. Also the thickness of the head of the seal cap may vary. Since the abutment and pressure members in said known apparatus are rigidly interconnected, and the bottle head has a fixed immovable position in relation to them at the compression of the resilient ring, the ring might be compressed against a not desired part of the bottle head at varying dimensions of the bottle neck and/or the seal cap. The bottle head will thereby readily be exposed to breakage owing to the fact that said members lack ability to adjust themselves for such variations.

The present invention has for its object to develop such an improvement of such apparatus to enable them to be reliably used independently of any occurring variations in the dimensions of the bottle head and the seal cap and without any danger of breaking the bottle head.

According to the invention, this is effected by arranging all of said three members (the abutment member, the pressure member, and the wedge member) axially movable in relation to each other. To this end the pressure member is suit-

ably arranged in such a way that the same being urged by a spring device or the like is allowed to automatically be displaced in relation to the bottle during the sealing operation for the purpose of adjusting itself for any occurring variations in the size or shape of the bottle neck or the thickness of the seal cap head or both. According to a suitable embodiment the pressure member is connected to an abutment member, which is displaceable in the longitudinal direction of the bottle, by means of a spring device in such a way that, when the abutment member is displaced through the action of the counter-pressure of the bottle, the resilient ring is displaced through the action of said spring device in relation to the guide face so as to be radially compressed.

Other features of the invention will be further described in connection with the following detailed description of an embodiment illustrated on the accompanying drawing.

Fig. 1 shows in elevation an assemblage of the principal parts of the apparatus.

Figs. 2 and 3 show elevations, partly in section, of the parts active in the attachment of the seal cap, Fig. 2 disclosing the positions of the parts before the sealing operation, and Fig. 3 the positions of said parts after completed sealing operation.

Fig. 4 shows a section along the line IV—IV in Fig. 3.

The apparatus consists of a frame 1 supporting two or more uprights 2, on top connected by means of a yoke 3, which in its centre supports the device 4 for attaching the seal cap. 5 designates a cross-member slidable up and down along the uprights 2, the bottle 5 to be placed on said cross-member. The lowest position of the bottle can be adjusted by means of an adjustable screw 7. When the seal cap is to be attached to the bottle, the bottle is pressed upwards towards the device 4 by moving the cross-member 5 upwards by means of any suitable operating device, not shown, for example a lever mechanism.

It is assumed that the bottle during this motion has reached the position indicated in Fig. 2 without the bottle yet exerting any pressure on the device 4. A vertical rod 8 is centrally secured to the yoke 3, for example by means of a screw and nut connection. The rod 8 which thus will be stationary is below provided with a neck 9 of smaller diameter. In a bore in the neck 9 a pin 10 is attached, the two protruding ends of which without play engage holes 11 in

the walls of a cylindrical sleeve 12, below called the wedge member, which member thus in the illustrated embodiment will be stationary in relation to the frame.

The rod 8 with the neck 9 and the wedge member 12 serve as guides for an axially displaceable abutment member 13. The rod 8 with the neck 9 is entered in bores 14 and 15 respectively of corresponding diameters in the abutment member 13, which at the bottom is ended by a recessed cylindrical part 16, which is entered in and guided by the bore in the wedge member 12. The lower end of the part 16 is to abut against the seal cap, for which reason its end surface is formed in a way corresponding to the form of the top of the seal cap as shown in Fig. 2.

17 is a spiral-spring which at the top is connected to the abutment member 13, suitably as shown in Figs. 2 and 3 by means of two studs 18, which at the bottom end are formed as hooks 19, said hooks supporting the spring at diametrically opposite points. The studs 18 are adjustably connected to the member 13 by means of the nuts 20 so as to adjust the tension of the spring as desired. The spring 17 is below connected with a pressure member 21. The lower part of the spring enters and is guided by a central bore 22 in the pressure member 21, and it is connected to the pressure member by means of pins 23 screwed into the wall thereof, which pins project above the coil of the spring to hold it at opposite points as shown. The pressure member 21 is further provided with a central bore 24, in which the lower part of the wedge member 12 is inserted. The pressure member 21 is further on the bottom side provided with an opening 25, into which the bottle head is to be entered. Between the opening 25 and the bore 24 the pressure member 21 is provided with an upstanding annular collar 26 on top terminated by a plane bearing surface 27, upon which a resilient ring 28 loosely rests. The top side of the resilient ring bears against a conical guide face 29 in the lower end of the wedge member 12.

In the position shown in Fig. 2, the resilient spring 28 also bears against the outside of the lower end of the cylindrical part 16. The spring 17 is strained and urges the members 13 and 21 towards each other. Hereby the collar 26 presses the ring 28 against the conical guide face 29 on the wedge member 12, whereas the abutment member 13 is pulled downwards but is stopped by the pin 10, which will abut against the upper end of an oblong hole 30 provided in the part 16, the hole 30 being positioned somewhat above the lower end of the bore 15. In this position axial plays are formed between the shoulder 31 on the rod 8 and the bottom of the bore 14 and between the end of the neck 9 and the bottom of the bore 15.

The resilient ring 28 may for instance consist of spirally wound wire, so as to form an annular spiral-spring. By winding it in close coils and making it of a suitable material, a ring is obtained with an excellent radial resiliency and at the same time so great power of resistance that it cannot be deformed by the pressure exerted by the spring 17. The ring 28 is suitably given a somewhat smaller diameter than the diameter of the part 16 so that the ring is somewhat widened when the lower end of the part 16 is entered into the ring. The ring should further be so dimensioned that upon completed

compression of the seal cap, the coils of the ring will abut or nearly abut against each other, whereby a mutual guiding is obtained between the coils which prevents any injurious action on the ring. The ring 28 may also be designed in any other suitable way provided that it obtains the requested qualities of resiliency. The inclination of the guide face 29 towards the longitudinal axis is suitably selected to be 45° or more, since a smaller angle readily causes the ring 28 to be keyed to the wedge member, particularly if the diameter of the wire coils of the ring 28 is small.

When the cross-member 5 and thus the bottle 6 are moved upwards, the bottle head with the seal 15 cap enters the opening 25 so that the top of the seal cap will abut against the end surface of the part 16. When the bottle is moved further upwards, the abutment member 13 is pressed upwards, until the bottom of the bores 15 and 14 or one of these will abut against the end of the neck 9 or the shoulder 31 respectively. This position is shown in Fig. 3. When the abutment member 13 was moved upwards, also the pressure member 21 was carried along by the spring 17, which thereby will be further strained, since the motion of the pressure member 21 cannot be as great as the motion of the abutment member 13. When the part 16 moves upwards, its lower end is brought out of the ring 28, which now instead will bear against the skirt of the seal cap. At the same time the pressure member 21 moves upwards so that the collar 27 will force the ring 28 to be displaced upwards along the beveled guide face 29. This causes the ring to be resiliently compressed in the radial direction, and the ring is pressed with increased force against the skirt of the seal cap. When the bottle has been raised so much that the annular recess 32 on the bottle head is at the same level as the resilient ring, the latter deforms the seal cap skirt in conformity with the shape of said annular recess, as shown in Fig. 3.

When the bottle thereupon is moved downwards, the members 13 and 21 will also move downwards, and the bead 33 on the bottle head forces the ring 28 to be widened so that the lower end of the part 16 again will be entered into and embraced by the ring. Thus all parts will automatically return to the positions shown in Fig. 2.

The bottom surface of the part 16 is preferably provided with a downwardly projecting annular edge so arranged that the same will be entered into the resilient ring 28, when the latter is widened by the bead on the bottle neck at the removal of the bottle, thus retaining the ring 28 in its initial position and preventing it from falling off.

Having now particularly described the nature of our invention and the manner of its operation what we claim is:

1. Apparatus for attaching seal caps on bottles, wherein the seal cap skirt is deformed to enter a recess on the bottle head, comprising an abutment member adapted to abut against the top of the seal cap, a ring enclosing the seal cap and adapted to be compressed resiliently in the radial direction around the seal cap, a pressure member supporting said ring and adapted to axially displace said ring, a wedge member provided with an inclined guide face adapted to cooperate with said ring and compress the same when the ring is axially displaced by the pressure member, said abutting member, pressure member, and wedge member being axially movably arranged in rela- 75

tion to each other, said abutment member being axially movable in relation to the bottle and connected to said pressure member by means of a spring member so that upon axial displacement of said abutment member through the pressure of the bottle, said spring member by means of said pressure member will displace the resilient ring along the guide face of the wedge member so as to radially compress the ring around the seal cap skirt.

2. Apparatus for capping bottles by deforming the skirt of a seal cap to enter a recess on the bottle head, comprising a bottle support, capping members, a support for said capping members, means for axially moving said supports in relation to each other to seal the bottle, said capping members comprising a resiliently compressible ring adapted to enclose the seal cap and to be compressed in radial direction around the seal cap, a counter member stationarily secured to the sup-

port for the capping members, a pressure member arranged axially movable in the last named support, said ring being arranged in an interspace between the counter member and the pressure member which are provided with surfaces abutting against the ring and so adapted that the ring is radially compressed when the counter member and the pressure members are moved towards each other, an abutting member arranged axially movable in the support for the capping members and adapted to abut against the top of the seal cap, and a spring device connecting said two axially movable members and adapted to yieldingly move the pressure member towards the counter member when the abutment member is 15 axially displaced through the action of the bottle until the capping operation has been completed.
